UNITED STATES PATENT OFFICE.

JAMES F. RALEIGH, OF RIVER FOREST, ILLINOIS, ASSIGNOR TO PINES WINTERFRONT COMPANY, OF CHICAGO, ILLINOIS, A CORPORATION OF DELAWARE.

THERMOSTATIC WAFER.

Application filed March 16, 1925. Serial No. 16,090.

My invention relates to thermostatic wafers of the type having extensive use in thermostatically-controlled radiator shutters, and in other mechanisms where thermal responsive means is employed to govern a valve, operate a shutter or to perform any other controlling or operating function.

One of the principal objects of the invention is to provide a mechanically pressed joint between the two halves of the wafer, in addition to the soldered joint which is usually provided between these wafer halves, for perfecting the hermetic seal of the wafer.

A further object of the invention is to increase the freedom of lateral flexure of the side walls of the wafer and the range of this flexure without endangering the hermetic seal at the periphery of the wafer.

Referring to the accompanying drawing illustrating my invention—

Figure 1 is a fragmentary sectional view through a thermostatically-controlled radiator shutter, showing a plurality of my improved wafers used in the shutter operating thermosstat.

Figure 2 is an edge view of one of the original blanks;

Figure 3 is a sectional view of the two completely formed shells or halves of the wafer before assembling;

Figure 4 is a sectional view through the wafer after assembly of the halves, but before the periphery has been creased and soldered; and

Figure 5 is an enlarged sectional view of the completed wafer.

For illustrating a typical use of these thermostatic wafers, I have shown in Figure 1 the upper-portion of a popular type of radiator shutter attachment now on the market which employs these wafers for mechanically opening or closing a plurality of shutter devices controlling the air-circulating flow through the radiator, in accordance with the temperature of the radiator. Such a radiator shutter is disclosed in my prior Patent No. 1,393,161, dated October 11, 1921.

One of the frame members of the device supports a heat-conducting plate 6 which is adapted to contact with the radiator core and this plate has supporting lugs or other supporting means for mounting one or more wafers 8. There are usually two or more of these wafers provided, the innermost one

contacting with the heat-conducting plate 6 and the outermost one bearing against a pallet 7 which transmits the cumulative expansion of the series of wafers through linkage, generally designated 9, to the radiator shutters. Heat-conducting spacers 11 are usually interposed between the wafers.

Referring now to the improved construction of the present wafer, it will be observed from Figure 2 that the wafer is built up of two shells or diaphragm walls 12 and 13, each having laterally extending flanges 12' and 13', respectively. The shells or diaphragms are substantial duplicates, except that one shell 12 is of slightly smaller diameter to nest its flange 12' snugly within the other shell.

Heretofore, in the construction of these wafers, the soldering operation has been performed with the shells merely nested together, as shown in Figure 4. The solder which is applied around the joint 14 between the two flanges will oftentimes merely cover this joint with a relatively thin film of solder. In the particular usage to which these wafers are applied, the expanding ether in the wafer will create a considerable pressure tending to separate the two shells and the flexure of the side walls will also tend to loosen the joint and separate the shells. Heretofore these stresses have all been borne by the soldered joint, and where the solder is thin it will sometimes crack, allowing the hermetic seal to break down.

I have obviated this difficulty by reinforcing the soldered joint with a mechanically pressed joint which carries these stresses and which also maintains the opposing surfaces of the flanges 12' and 13' in close engagement so that solder flowing therebetween can solder the two flanges together across their entire widths.

In securing the two shells together according to the present invention, the telescoping flanges 12' and 13', after being nested, are subjected to an operation which produces a mechanically pressed joint between the flanges. This operation is a creasing or grooving operation performed on the outer periphery of the wafer, during which lateral pressure is concurrently placed on the peripheries of the wafer shells for pressing the two shells together. The lateral pressure locks the edge 16 of the innermost flange 12' in the corner between the side wall 110

and the peripheral flange of the other shell 13. Consequently, when the grooving pressure is applied to the outer periphery of the wafer the edge 16 will be locked in this corner and will not allow this inner flange to be deflected inwardly (such as it would do if its outer edge were free), but will compel this inner flange to assume the curve of the outer flange, substantially as indicated by 10 the annular groove depression 18. Because both flanges must take this grooved formation, a close mechanical joint is secured across the entire width of the flanges and also at the point where the edge 16 is pressed 15 into the inner corner of the outer flange 13'. Lateral pressure may be employed to slightly bevel or round the outer corners of the wafer, this rounding operation tending to roll the edge 19 of the outer flange inwardly 20 over the side of the other shell 12.

The next operation is to solder this seamed or grooved joint between the two shells by dipping or turning the periphery of the wafer in hot solder. This solder will seal 25 the joint occurring at the edge 19, as indicated by the solder 21, and will enter in between the two flanges 12' and 13', thereby sealing these flanges across their entire width. After this hermetic seal has been 30 completed, the wafer is charged with ether, or any other suitable fluid or gas, through a small hole in one of the shells, which is then closed by a drop of solder.

Supplementary to this practice of forming 35 a mechanically pressed joint between the flanges, I contemplate forming an annular groove or bead 22 in the face of each shell (in the operation of forming the shell) for confining the flexure of the diaphragm wall 40 to the central part of the wafer. By the provision of these beads or grooves the inward and outward flexure of the two side walls of the shells will extend out to the annular grooves or beads 14, with practically 45 no deflection of the metal from the groove or bead out to the soldered joint. Hence, there will be practically no tendency to loosen or crack this soldered joint as a result of the flexure of the shell walls. The 50 presence of the grooves or bead 22 also permits a greater range of flexure of each shell wall in the expansion and contraction of the wafer under change of temperature.

Having described my invention, what I 55 claim is:

1. A thermal cell comprising a pair of side members provided with marginal

flanges disposed one within the other, said flanges concavo-convex with the concave surface of one flange embracing the convex surface of the other flange.

2. A thermal cell including a pair of sheet metal shells, each comprising a flanged disc, the flanges of said discs being nested one within the other with the inner flange disposed edgewise against the disc by which the outer flange is carried, said flanges being concavo-convex with the concave surface of the inner flange embracing the convex surface of the outer flange.

3. The method of joining a pair of flanged side members of a thermal cell which consists in nesting the flanges of the side members one within the other and peripherally grooving said flanges to interlock them.

4. The method of joining a pair of flanged side members of a thermal cell which consists in nesting the flanges of the side members one within the other, peripherally 80 grooving said flanges to interlock them and simultaneously pressing the side members together.

5. A thermal cell comprising a pair of side members joined together, the contacting surfaces of the side members being concavo-convex with the convex surface of one member received by and soldered to the concave surface of the other member.

6. In a thermostatic wafer, the combination of a pair of shells, flanges on said shells nesting one within the other, said flanges being grooved inwardly whereby they are both curved concentrically across their entire width, solder sealing the joint, 95 and an annular groove formed in each of said shells adjacent its flange.

7. The method of joining a pair of flanged side members of a thermal cell which consists in nesting the flanges of the side members one within the other, pressing the side members together and simultaneously 100 forming interlocking deformations in said nested flanges.

8. The method of joining a pair of 105 flanged side members of a thermal cell which consists in nesting the flanges of the said side members one within the other, forming interlocking deformations in said nested flanges and solder sealing the joint.

In witness whereof, I hereunto subscribe my name this 11th day of March, 1925.

JAMES F. RALEIGH.
